UNITED STATES PATENT OFFICE.

WILLIAM H. C. HIGGINS, JR., OF LAPORTE, INDIANA.

CARBURETER.

1,077,910.

Specification of Letters Patent.

Patented Nov. 4, 1913.

Application filed October 14, 1910. Serial No. 586,975.

To all whom it may concern:

Be it known that I, WILLIAM H. C. HIGGINS, Jr., a citizen of the United States, residing at Laporte, in the county of Laporte and State of Indiana, have invented a certain new and useful Improvement in Carbureters, of which the following is a specification.

My invention relates to improvements in carbureters, and one application of it is illustrated in the accompanying drawings, wherein—

Figure 1 is a plan view; Fig. 2, a section on the line 2—2 of Fig. 1; Fig. 3, a section on the line 3—3 of Fig. 2; and Fig. 4, a section on the line 4—4 of Fig. 2.

Like parts are indicated by the same letter in all the figures.

A is a shell which with the wall A¹ forms the vacuum chamber A².

B is a hydrocarbon or fuel valve supplied from the pipe B¹, and provided with a nozzle B² which discharges into the vacuum chamber. The pipe B¹ leads to near the bottom 25 of a fuel tank B³ which is supplied from any convenient source with fuel which is kept, say at the constant level B⁴, by means of an overflow pipe B⁵ which may lead to any reservoir. C is a somewhat similar

30 water valve provided with the supply pipe C¹ and with the nozzle C² which discharges into the vacuum chamber. The pipe C¹ leads into the bottom of the tank C³ which is supplied from any convenient source, and

35 the water in which is maintained at the level C⁴ by the overflow pipe C⁵. I have shown the water level as lower than the oil level, and the water valve as higher than the oil valve. This particular arrangement

40 is not essential; but the arrangement must be such that the oil valve will feed responsive to a lower vacuum than the water valve. These valves are used for the purpose of adjusting or determining the correct cross

45 sectional area of the discharge; and, as indicated in Fig. 4, they are arranged so that when adjusted for operation, the annular discharge way B⁶ is smaller in cross sectional area than the annular discharge way

50 C⁶ of the water valve. The object of this arrangement is to give a more abundant feed of water than of oil when the two are feeding simultaneously. The precise arrangement and proportions of these several parts

55 are to be taken in a sense as diagrammatic, being intended to illustrate the principle,

rather than to give a perfectly exact reproduction of a particular piece of mechanism.

D is a mixture discharge port, and D¹ the connection which leads thence to the engine. 60 The usual engine valve for admission of the mixture is not shown.

E E¹ are the two parts of an air-supply port separated, for convenience, as herein-after explained. One of them is controlled 65 by the shutter E², and both open into the air passage-way E³.

F is a slide valve, having a hole F¹ therein, and adapted to control, as indicated, the mixture discharge port and the air supply 70 port, and operated in any desired manner or by any desired motive power by means of the lever F² which passes out through the case.

I have spoken of hydrocarbon and water 75 valves, but the essential point is that I connect to the carbureter a hydrocarbon and a water supply pipe, in the manner proposed. The valves are only for the purpose of adjusting the sizes of the apertures; but in 80 each case the oil or water is drawn from the supply pipes and tanks by the vacuum in the vacuum chamber. It is that vacuum which causes the fluid to flow; and by varying the vacuum, the flow of fluid is varied. 85

The devices, whatever they are, must be adjusted, related and connected and set so that the oil or fuel will flow with practically any degree of vacuum from minimum load to maximum load, but so that the water 90 will only begin to effectively flow, at more than minimum load, and preferably at about half load, and thereafter more rapidly than the oil. In other words, two valves do not respond equally to the same vacuum, or 95 speaking in more general terms, the two inlets or supplies for oil and water respectively do not respond equally to the same vacuum. This is due, as explained, to the difference in the sizes of the supply openings and the difference in the heights to 100 which the oil and water are to be lifted.

It will be evident that although I have shown in my drawings an operative device, many changes might be made, both in size, 105 shape and arrangement of parts, without departing materially from the spirit of my invention; and I wish therefore that my drawings may be regarded as in a sense dia-grammatic.

The use and operation of my invention are as follows: My invention is particularly

adapted for use in connection with a vacuum chamber carbureter where the vacuum in the carbureter varies in the opposite direction from the vacuum in the engine cylinder, that is to say, where the vacuum in the carbureter increases as the vacuum in the engine cylinder decreases, and vice versa. As the engine operates, it draws its charge from and through the carbureter, and because of the relation of the mixture discharge and air intake ports, a vacuum is set up in the carbureting chamber. This vacuum is varied by means of the sliding valve which controls both intake and mixture discharge openings, and may be adjusted or varied by means of the adjustable shutter which controls a portion of the air intake opening. It will be observed that for maximum power the mixture discharge port is at its maximum opening, thus allowing a very free flow of air and fuel through the carbureter to the engine. At the same time however, the relation between the discharge port and air intake port is such that the vacuum in the carbureting chamber is at its maximum, as the power or speed of the engine decreases the mixture discharge port is closed and closes more rapidly than the demand of the engine. The result of this is to increase the vacuum in the engine cylinder, but at the same time the relation between the mixture discharge and air intake ports is such that the vacuum in the carbureting chamber is decreasing and the result is that as the vacuum in the carbureting chamber decreases, the vacuum in the engine cylinder itself increases and vice versa. The sliding valve F^1 being controlled by any suitable means, therefore, causes a suitable vacuum in the carbureter chamber, which vacuum draws from both valves or inlets the requisite amount of fuel and water. The shutter and slide valve are so adjusted as to give the desired result by manipulation of the shutter at different loads until its true position for a given engine is determined, whereupon it is fixed in position. The maximum amount of water and the maximum amount of hydro-carbon are usually both supplied for a maximum load, but by test, the proper size of aperture and the proper lift of fluid is arrived at, so that the water begins to feed in appreciable quantities at something like a load half way between minimum and maximum, and so that thereafter the water feeds more rapidly, until at maximum load there is frequently a relatively large amount of water supplied, and the amount of water may be equal to the amount of oil. The valves being set at this point, the carbureter is ready for use.

I have shown my invention as applied to a particular form of air and mixture controlling apparatus; but my invention, so far

as it relates to the joint use of fuel and water, and the method of feeding both by variations in the vacuum produced in the carbureter, is of course equally applicable to other forms of devices.

Broadly speaking, the invention has reference to introducing both water and fuel into a carbureter chamber where there is means for varying the vacuum in said chamber and for varying the effective areas of the air inlet and mixture outlet unequally.

It will of course, be understood that when the adjustment by the shutter E^2 has been effected, for any given engine, no further adjustment is necessary and the carbureter thereafter operates just as if the various apertures or ports or other equivalents had been arranged, shaped and positioned so as to get the desired result without such shutter adjustment. In other words, the operation of the water supply is just the same, regardless of the manner in which the proper areas and dispositions of the various ports have been arrived at and regardless of the number of air ports or air port sections. The essential point is that the water like the oil is fed to the mixing chamber of the carbureter responsive to variations in the vacuum in such mixing chamber.

It will be understood, of course, that my invention is applicable to the use of any kind of hydro-carbon fuel such as oil, gasoline, alcohol and other similar fluids.

In my drawings I have not shown an engine, nor any other part of an apparatus in connection with which my carbureter might be used, but it will be understood that the pipe or opening D^1 may lead to the combustion chamber of an explosive engine, and it will also then be understood that the lever F^2 may be connected with the usual governor.

What I claim as new, and desire to secure by Letters Patent, is:—

1. In a carbureter, a vacuum carbureting chamber having fuel and water inlets each having a nozzle opening into the carbureter chamber separate and distinct one from the other, the latter adapted to feed only after the vacuum has substantially varied from its condition of no-load, and both adapted to vary but unequally their feeds responsive to variations in the vacuum of the carbureting chamber, and an air inlet and a mixture outlet, in combination with means for simultaneously but unequally varying both of their effective areas during operation, and separate means for adjusting the effective area of one of them.

2. In a carbureter, a vacuum carbureting chamber having fuel and water inlets each having a nozzle opening into the carbureter chamber separate and distinct one from the other, the latter of larger effective area than the fuel inlet during operation and adapted

to feed only after the vacuum has substantially varied from its condition at no-load, and both adapted to vary but unequally their feeds responsive to variations in the 5 vacuum of the carbureting chamber, and an air inlet and a mixture outlet, in combination with means for simultaneously but unequally varying both of their effective areas during operation, and separate means for 10 adjusting the effective area of one of them.

3. In a carbureter, a vacuum carbureter chamber having fuel and water inlets each having a nozzle opening into the carbureter chamber separate and distinct one from the 15 other and adapted to vary their feeds responsive to variations in the vacuum in the carbureter chamber, the water inlet adapted to feed only after the vacuum has substantially varied from its condition of no load 20 and after the oil has been feeding, and an air inlet and a mixture outlet in combination with means for simultaneously but unequally varying both of their effective areas during operation.

25 4. In a carbureter, a vacuum carbureter chamber having fuel and water inlets each having a nozzle opening into the carbureter chamber separate and distinct one from the other and adapted to vary their feeds responsive to 30 variations in the vacuum in the carbureter chamber, means for maintaining the liquids which flow to said fuel and water inlets under different pressures, and an air inlet and a mixture outlet in combination 35 with means for simultaneously but unequally varying their effective areas during operation.

5. In a carbureter, a vacuum carbureter chamber having fuel and water inlets, each 40 having a nozzle opening into the carbureter chamber separate and distinct one from the other and adapted to vary their feeds responsive to variations in the vacuum in the carbureter chamber, means whereby the liquid 45 supplies for the inlets are maintained under different heads so as to have different pressures, and an air inlet and a mixture outlet in combination with means for simultaneously but unequally varying both of their 50 effective areas during operation.

6. In a carbureter, a vacuum carbureter chamber having fuel and water inlets, each having a nozzle opening into the carbureter chamber separate and distinct one from the 55 other and adapted to vary their feeds responsive to variations in the vacuum in the carbureter chamber, the water inlet adapted to feed only after the vacuum has substantially

tially varied from its condition of no load and after the oil has been feeding, means 60 for maintaining the liquids which flow to said fuel and water inlets under different pressures, and an air inlet and a mixture outlet in combination with means for simultaneously but unequally varying both of their effective areas during operation.

7. In a carbureter, a vacuum carbureter chamber having fuel and water inlets each having an adjustable valve and a nozzle opening into the carbureter chamber separate and distinct one from the other and adapted to vary their feeds responsive to 70 variations in the vacuum in the carbureter chamber, the water inlet adapted to feed only after the vacuum has substantially 75 varied from its condition of no load and after the oil has been feeding, and an air inlet and a mixture outlet in combination with means for simultaneously but unequally varying both of their effective areas during 80 operation.

8. In a carbureter, a vacuum carbureter chamber having fuel and water inlets, each having an adjustable valve and a nozzle opening into the carbureter chamber separate and distinct one from the other and adapted to vary their feed responsive to 85 variations in the vacuum in the carbureter chamber, means whereby the liquid supplies for the inlets are maintained under different 90 heads so as to have different pressures, and an air inlet and a mixture outlet in combination with means for simultaneously but unequally varying both of their effective areas during operation.

9. In a carbureter, a vacuum carbureter chamber having fuel and water inlets, each having an adjustable valve and a nozzle opening into the carbureter chamber separate and distinct one from the other and 100 adapted to vary their feeds responsive to variations in the vacuum in the carbureter chamber, the water inlet adapted to feed only after the vacuum has substantially 105 varied from its condition of no load and after the oil has been feeding, means for maintaining the liquids which flow to said fuel and water inlets under different pressures, and an air inlet and a mixture outlet in combination with means for simultaneously 110 but unequally varying both of their effective areas during operation.
